UNITED STATES PATENT OFFICE.

ERNST J. MULLER, OF BUTTE, MONTANA.

ORE-JIGGER.

SPECIFICATION forming part of Letters Patent No. 737,264, dated August 25, 1903.

Application filed July 26, 1897. Serial No. 645,917. (No model.)

To all whom it may concern:

Be it known that I, ERNST J. MULLER, of Butte, in the county of Silverbow and State of Montana, have invented certain new and useful Improvements in Ore-Jiggers; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My improvements pertain to that class of ore washing, separating, and concentrating apparatus commonly called "ore-jigs" or "ore-jiggers."

The main objects of the invention are to accurately regulate and control the pulsations of water by which the separation of the particles of ore from the gangue or impurities according to density or specific gravity is effected and generally to improve the construction and operation and to increase the efficiency of this class of machines.

It consists of certain novel features in the construction and arrangement of component parts of the machine, as hereinafter particularly described, and pointed out in the claims.

In the accompanying drawings like letters designate the same parts in the several figures.

Figure 1 is a vertical cross-section of an ore-jigger embodying my improvements, the plane of the section being indicated by the line 11, Fig. 6. Fig. 2 is a detail view, on an enlarged scale, of one of the adjustable eccentricities and its connections for actuating the plungers. Figs. 3 and 4 are sections thereof on the lines 33 and 44, respectively, Fig. 2. Fig. 5 is a section on the line 55, Fig. 3, showing the hub of the eccentric. Fig. 6 is a horizontal section showing in broken plan view one of the plunger-compartments of the jigger; and Fig. 7 is a vertical section on the line 77, Fig. 6, showing on an enlarged scale the guiding device and the eccentric-rod connection of a plunger.

In the operation of machines of this class to which my improvements pertain the ore having been crushed to liberate the metal from the worthless rock or gangue and prop-

erly sized by screening is fed upon the screens of the jig. The particles of mingled metal-bearing ore and rock or gangue are caused by the pulsations of water through the screens to arrange themselves according to density or specific gravity in layers, the heavier particles containing most metal seeking the lower level and the lighter particles rising to or remaining in the upper strata of ore. The heavy metal-bearing ore passes through the screens and constitutes the concentrates, while the lighter particles of rock or gangue are conducted off as tailings. In treating ores of different grades, particularly the fine meal sizes and slimes, it is necessary to regulate and control the pulsations of water, and it is sometimes desirable to produce a more rapid impulse or movement of the water upward than downward, thereby allowing more time for the ore particles to settle and arrange themselves in distinct layers. To successfully regulate and control the pulsations of the water by which the separation of the ore is effected, it is necessary not only that provision be made for changing and adjusting the stroke of the plungers, but also that they be closely fitted in the compartments of the tank, so as to prevent the free passage of water between the edges of the plungers and the walls of the compartments in which they work. My improvements are calculated to secure these ends.

Referring to the drawings, and particularly to Figs. 1 and 6, A designates a tank constructed in the usual way of plank and supported by a framework B. It is divided by a vertical partition a into compartments C and D, which communicate with each other below said partition. Each compartment C is provided with a horizontally-disposed sieve or screen E, upon which the ore to be treated is deposited. Each compartment D is provided with a plunger F, which is constructed in the usual way of three layers or tiers of plank, the grain of the middle layer or tier crossing that of the others. Each of the plunger-compartments D is provided with a lining d, of wood, the grain of which runs vertically, and the plunger F is fitted closely in said lining, so as to prevent the passage of water from one side of the plunger to the other around its edges.

G is a guide consisting of a cast-iron cross-piece spanning the upper part of the compartment D centrally and bolted at its ends to the walls of said compartment. It is formed with a vertical cylindrical opening and above and around said opening with a flange g, which serves to hold oil around the hollow plunger-trunk.

H is a tubular or hollow trunk fitted in the opening of the guide G and bolted at its lower end to the upper side of the plunger. It is open at its upper end and provided near its lower end with a cross-pin h.

I is a horizontal driving-shaft carried by bearings on the framework B over the plunger-compartments D lengthwise of the machine. It is provided over each plunger-compartment in line with the plunger-trunk H with an adjustable eccentric K, composed, as shown in Figs. 2 to 5, inclusive, of two parts—a hub k, keyed or otherwise fixed on the shaft I, and a rim k', adjustably mounted upon said hub. The hub is formed at one end with a flange k² and at the opposite end with an ear k³, perforated transversely to and in a line intersecting the axis of the hub. The web of the rim k' is formed with an oblong opening, the longer sides of which are extended laterally into parallel flanges or bearings k⁴ k⁴, which are fitted to flattened sides of the hub, as shown in Figs. 2 and 3. On opposite sides of this opening and parallel therewith said web is formed with slots k⁵ k⁵, and at one end of said opening in line with the ear k³ on the hub it is formed with an ear k⁶. In this ear is threaded an adjusting screw or bolt L, which passes through the plain bore of the ear k³ and has a squared head fitting the space between said ear and the adjacent side of the eccentric-shaft I. This screw serves to move the rim of the eccentric radially upon its hub for varying the throw of the eccentric. The rim is held to the hub of the eccentric by bolts M M, passing through the slots k⁵ in the web of the rim, and holes in the flange k² of the hub and serving to clamp the parts firmly together when adjusted. The web of the rim is provided on one side of the opening therein with an index-mark n, in line with the center of its circular periphery, and the end of the hub adjacent thereto is provided with a scale o, the zero-point of which is in line with the center of the hub and the axis of the eccentric-shaft. Each main division of this scale in the present case indicates one-inch throw or eccentricity and each of the smaller subdivisions a quarter of an inch throw. When the index-mark on the web of the rim is placed on the zero-mark of the scale, the periphery of the rim is concentric with the bore of the hub and the axis of the eccentric-shaft, so that the throw of the eccentric can be varied from nothing to four inches.

N is the eccentric-strap, made in two parts, which are bolted together upon the rim of the eccentric. The lower half of said strap is formed with a radial sleeve or socket n',

having a longitudinal keyway n² intersecting it. The periphery of the eccentric is preferably made convex or formed to the segment 70 of a sphere, and the strap is fitted thereto, so as to retain it in place thereon and permit it to turn laterally without binding.

O is a rod, one end of which is fitted in the sleeve n' and secured therein by a key o', 75 passing through a keyway therein and the keyway in said sleeve, and by a nut o², threaded on said rod and adapted to abut against the end of said sleeve. At its lower end said rod is provided with a box, through 80 which the cross-pin h in the plunger-trunk H passes, pivotally connecting the plunger with said rod, as shown in Figs. 1, 6, and 7. This box is composed of two parts p and p'. The upper part p is formed perpendicular to its axis with 85 a sleeve or socket p², in which the lower end of the eccentric-rod O is threaded and pinned or otherwise rigidly secured. Both parts of the box are formed on opposite sides with correspondingly-perforated ears, and on the rod O 90 is loosely fitted a cross-head p³, which is connected with the cap or lower part p' of the box by bolts p⁴ p⁴, passing through the perforated ears of said cap and upper box-section and through corresponding holes in the cross-head, as shown in Fig. 1. Between the upper end of the sleeve p² and the cross-head p³ is interposed a spiral spring Q, which tends to draw the cap p' upwardly toward the other part of the box and to take up all wear or play 95 between said box and the pin h. The hollow trunk H not only serves to guide the plunger in its reciprocating movement, thereby admitting of a closer fit between the plunger and the walls of the compartment in which it 100 works, but it also serves as a housing for the eccentric-rod connection with the plunger and as a receptacle to hold oil for the thorough lubrication of said connection. The upper end of the trunk being open admits of readily supplying it with oil at any time. Each plunger-compartment is provided with a covering d', which is fitted around the rim g of the plunger-guide and rests upon the upper face of said guide, which serves as a support therefor. 105 This serves to prevent the splashing of water out of the tank by the plungers and also excludes from the compartments D ore or other matter which would obstruct or interfere with the operation of the plungers. The covering d' does not have an air-tight fit in the plunger-compartment of the tank, and sufficient vent 110 for the operation of the plunger is thus provided. The plunger having a comparatively short stroke, varying according to the nature 115 of the ore from a fraction of an inch to about four inches, and the space above it ordinarily containing but little water, very little or no vent is necessary, the air contained in the compartment readily expanding and condensing 120 sufficiently to offer little resistance to the ordinary movements of the plunger. The annular recess formed by the rim or flange g around the upper end of the trunk H being 125 130

exposed above the cover *d*' can be readily supplied with oil at any time for the lubrication of said trunk.

The connecting device hereinbefore described between the eccentric strap and rod facilitates the assemblage of the driving mechanism, which, together with the guiding device, not only affords means of readily and accurately adjusting the movement or throw of the plungers, but also admits of the employment of close-fitting plungers and renders their operation positive and steady. In this way the pulsations of water through the screens are successfully regulated and controlled, as desired, according to the quality or nature of the ore to be treated, the efficiency of the machine is increased, and the quality of work performed by it is improved.

My improved adjustable eccentric will be found of special advantage in connection with any form of variable-speed driving mechanism, such as eccentric-gears, for imparting a faster downward and a slower upward movement of the plunger, whereby the fall of water through the associated screen is retarded, because the adjustment of the eccentric to vary its throw does not change its angular position on the eccentric-shaft or its relation with respect to the plunger driving mechanism, the adjustment of the rim of the eccentric being radial instead of angular.

I claim—

1. In an ore-jigger the combination with a tank separated by a partition into compartments which communicate with each other below said partition, and a horizontally-disposed screen and vertically-movable plunger arranged in said compartments on opposite sides of said partition, of a guide arranged in the upper part of the compartment containing the plunger, a hollow trunk attached to and extending upwardly from the plunger into an opening in said guide in which it is adapted to reciprocate, a driving-shaft extending horizontally over said tank and provided above the plunger-trunk with an eccentric and strap, a rod attached at its upper end to said strap and provided at its lower end with a box which is pivoted on a cross-pin in the lower part of said trunk, said box being composed of two parts, one formed with a socket in which the lower end of the rod is secured, and the other being connected by bolts with a cross-head loosely mounted on said rod, and a spring interposed between the upper box member and said cross-head, substantially as and for the purposes set forth.

2. In an ore-jigger the combination with a plunger and a shaft provided with an eccentric having a strap fitted thereon, of a stationary guide located above the plunger, a hollow trunk extending upwardly from the plunger into said guide in which it is adapted to reciprocate, a rod attached at its upper end to the eccentric-strap, a box having a socket in which the lower end of said rod is secured, a cross-head loosely mounted on said rod, a spring interposed between said box and cross-head, and a box-cap or adjustable member connected with said cross-head by bolts passing through and guided in said box parallel with the eccentric-rod, and a pin passing transversely through the lower part of said trunk and the box on the lower end of the eccentric-rod, substantially as and for the purposes set forth.

3. In an ore-jigger the combination with the tank, a plunger fitted to reciprocate in a compartment thereof, and an eccentric and its strap mounted on a shaft extending over said compartment, of a horizontally-disposed guide secured to the walls of said tank and having a vertical opening which is enlarged at its upper end to hold oil, a tubular trunk attached to said plunger and fitted in the opening of said guide, and a rod attached at its upper end to the eccentric-strap and pivoted at its lower end on a cross-pin in said trunk, substantially as and for the purposes set forth.

4. In an ore-jigger the combination with a tank, a plunger fitted to work in a compartment thereof and an eccentric and its strap mounted on a shaft extending over said compartment, of a guide bridging said compartment, attached at its ends to its walls and having a vertical opening and an upwardly-projecting flange around said opening for holding oil, a cover for said compartment supported on said guide and fitted around the flange thereon, a hollow trunk attached to the plunger and fitted in the opening of said guide, and a rod pivoted at its lower end in said trunk and connecting it with the eccentric-strap, substantially as and for the purposes set forth.

In testimony that I claim the foregoing as my own I affix my signature in presence of two witnesses.

ERNST J. MULLER.
